UNITED STATES PATENT OFFICE.

ERNEST BISCHOFF, OF PEKING, CHINA.

DESIGN FOR A RUG.

45,850.

Specification for Design.

Patented June 2, 1914.

Application filed April 3, 1914. Serial No. 829,375. Term of patent 14 years.

To all whom it may concern:

Be it known that I, ERNEST BISCHOFF, a subject of the Emperor of Germany, residing at Yang jou Hutung, in the city of Peking, China, have invented a new, original, and ornamental Design for Rugs, of which the following is a specification, reference being had to the accompanying drawing, forming a part thereof.

In the drawing, Figure 1 is a view of the upper left hand quarter of the rug. Fig. 2 is a view of the lower left hand quarter of

the rug. Fig. 3 is a view of the upper right hand quarter of the rug, and Fig. 4 is a view of the lower right hand quarter of the rug. When the four figures are combined they show the completed rug.

I claim:

The ornamental design for a rug, as shown.

ERNEST BISCHOFF.

In presence of—

EDWIN A. PACKARD,
G. McGRAW.
